Primary Examiner — Richard Kearney*Assistant Examiner* — Michael Hoffman(74) *Attorney, Agent, or Firm* — Spano Law Group;
Joseph S. Spano(57) **CLAIM**

The ornamental design for a metered dose inhalation monitor, as shown.

DESCRIPTION

FIG. 1 is a front elevational view of a metered dose inhalation monitor showing my new design;

FIG. 2 is a back elevational view thereof;

FIG. 3 is a top plan view thereof;

FIG. 4 is a bottom plan view thereof;

FIG. 5 is a left elevational view thereof; and,

FIG. 6 is a right elevational view thereof.

The broken lines depicted in the drawings illustrate portions of the article of manufacture to which the ornamental design has been applied, are for illustrative purposes only, and form no part of the claimed design.
